CHAIR BACK CONSTRUCTION

Erving B. Morgan and Royce W. Clay, Grand Rapids, Mich., assignors to American Seating Company, Grand Rapids, Mich., a corporation of New Jersey

Application June 25, 1948, Serial No. 35,168

10 Claims. (Cl. 155—194)

1

The present invention relates to chairs and more particularly to chairs of the type used in theaters and auditoriums.

The primary objects of the invention are to provide an improved chair back construction in which the ornamental sheet metal panel for the upholstered chair back extends well below the back to provide a shield for the rear of the chair seat, thus to prevent an occupant of a chair to the rear from placing his feet on said chair seat and soiling it, and also to protect the feet of the occupant of the chair to the rear against becoming pinched between the chair back and the chair seat during lowering movement of said seat from a raised position of non-use to a lowered position for occupancy; and generally to provide such an improved chair back construction which is reasonably economical in manufacture and attractive in appearance.

These and any other and more specific objects are attained by, and the invention finds preferable embodiment in, the chair structure hereinafter particularly described and illustrated by the accompanying drawings; wherein:

Figure 1 is a rear elevational view of a chair of the theater type;

Figure 2 is a side elevational view of the same showing certain parts thereof in section taken on line 2—2 of Figure 1;

Figure 3 is an enlarged fragmentary view of parts of the chair, shown partly in top plan and partly in oblique section taken on line 3—3 of Figure 2;

Figure 4 is an enlarged central vertical sectional view of the chair back and showing the fastening means for attaching the chair back to a supporting standard therefor, said standard being here shown fragmentarily; and

Figure 5 is an enlarged fragmentary vertical sectional view of certain parts of the chair back, the section being taken on line 5—5 of Figure 3.

Referring now in detail to these drawings wherein like parts are designated by the same numerals in the several views, the chair there shown is of the theater type which chairs are generally mounted in rows on spaced upright supporting standards 10 having arm rests 11 thereon. A chair seat 12 is mounted on and between spaced standards 10 in any known manner as by means of arms 13 on opposite sides of the chair which are seated in sockets 14 on the standards, and the chair seat is preferably turnable on the horizontal portions of the arms 13 to the lowered position of occupancy shown in full lines in Figure 2 and to a raised position of non-

2

use indicated by dotted lines in the same view.

The chair back comprises a rearwardly bowed foundation panel 15 which may be fabricated from any suitable material such as plywood, solid wood, metal or plastic, over the forward surface of which panel is disposed suitable upholstering materials which may include springs but as here shown comprise a layer of hair or cotton padding 16 and an outer upholstery cover 17 of fabric, leather or the like the marginal edges of which are drawn rearwardly around the foundation panel 15 and secured as by tacks 18 to the rear surface of said panel (see Figure 3). T-nuts 19 are inserted in pairs of apertures 20 at 10 the opposite sides of the foundation panel during the upholstering operation, and the heads of these T-nuts 19 bear against the front surface of the foundation panel to prevent the withdrawal of the T-nuts rearwardly through the 15 apertures 20. Wing clips 21 are secured to the rear surface of the foundation panel at opposite sides of said panel by means of bolts 22 which are inserted through apertures in the wing clips 21, through the upholstery cover 17, and 20 threaded into the T-nuts 19. The wing clips 21 have forwardly extending portions 23 by means of which the clips and the chair back are secured to the supporting standards 10.

The chair back has an ornamental sheet metal 25 back panel generally designated 24 which has its upper arcuate edge 25 curled forwardly to form a socket which embraces the upper edge of the upholstered chair back when these parts are assembled. The sheet metal back panel 24 is 30 vertically elongated and laterally or rearwardly bowed thus forming forwardly extending attachment side wings 26 which lie adjacent the wing clips' forwardly extending portions 23. The assembled chair back and ornamental back panel 35 are attached to the supporting standards 10 by fastening means comprising lower screws 27 passing through aligned apertures in the forwardly extending side wings 26 of the back panel 24 and in the forwardly extending portions 23 of 40 the wing clips 21, these lower screws 27 being threaded in the standards 10. Upper screws 28 secure the chair back and back panel to the standards 10 in selectively inclined position, said upper screws 28 being passed through a registering pair of apertures 29 in the opposite wing clips 21 and threaded in the standards 10. The apertures 29 in the wing clips 21 are arranged in arcs concentric with the lower attachment screws 28 so that after the lower screws have 45 been placed, the back may be turned to selected 50 lines in Figure 2 and to a raised position of non-

incline and the upper attachment screws 28 then placed.

The ornamental sheet metal back panel 24 is rearwardly bowed substantially throughout its vertical length and is rearwardly bent intermediate its ends to thus form an upper portion 30 and a lower portion 31 which portions are angularly disposed to each other and this angular disposition is maximum at the longitudinal center of the panel, diminishing to zero at the sides of the panel. The upper portion 30 of the ornamental sheet metal panel 24 is upwardly-rearwardly inclined and lies adjacent the upwardly-rearwardly inclined upholstered chair back. The lower portion 31 of the panel 24 depends substantially vertically from the upper portion 30, rearwardly of the chair seat, so that the lower portion 31 forms a shield for the chair seat and also permits free turning movement of the seat. The metal which joins the upper and lower portions 30 and 31 of the back panel 24 is drawn rearwardly to form a laterally and substantially horizontally extending ridge 32 of substantial dimensions at the middle of the panel and fading out at the sides of the panel. It will be seen that the ridge 32 serves the threefold purpose of ornamenting the chair in a harmonious manner, of increasing the rigidity of the back panel, and of taking up the metal to a substantial degree in the center of the back panel 24 where the angle between the upper portion 30 and lower portion 31 is most acute and to a lessening degree toward the outer sides of the panel.

The edges of the lower portion 31 of the back panel 24 are preferably strengthened and made smooth by curling, as indicated at 33 in Figure 4. Rearwardly stamped embossings 34 at the opposite sides of the upper portion 30 of the back panel 24 further strengthen the panel and also serve to accommodate the heads of the bolts 22 which secure the wing clips 21 to the foundation panel 15 of the chair back.

It will thus be seen that a chair structure has been provided in which the chair seat is shielded from the occupant of a chair to the rear by means of a novel chair back construction and while but one specific embodiment of the invention has been herein shown and described, it will be understood that many details of the construction shown may be altered or omitted without departing from the spirit of the invention as the same is defined by the following claims.

We claim:

1. A back panel for a chair structure comprising a vertically elongated sheet metal panel rearwardly bowed substantially throughout its length and provided with substantially parallel side wings for attachment of the panel to the chair structure, said panel being rearwardly bent intermediate its ends to thus form upper and lower portions angularly disposed to each other, said angular disposition being maximum at the longitudinal center of the panel and diminishing to zero at the sides of the panel.

2. A back panel for a chair structure comprising a vertically elongated sheet metal panel rearwardly bowed substantially throughout its length and provided with substantially parallel side wings for attachment of the panel to the chair structure, said panel being rearwardly bent intermediate its ends to thus form upper and lower portions angularly disposed to each other, said angular disposition being maximum at the longitudinal center of the panel and diminishing to zero at the sides of the panel; and the metal of

the panel joining the upper and lower portions thereof being drawn rearwardly to form a laterally extending ridge of substantial dimensions in the middle of the panel and fading out at the sides of the panel.

5. A chair back comprising: a rearwardly bowed sheet metal back panel having integrally formed upper and lower portions, the upper portion being inclined upwardly-rearwardly and the lower portion depending substantially vertically from the upper portion, the metal of the panel joining said upper and lower portions being drawn into a substantially horizontal ridge of substantial dimensions in the middle of the panel and fading out at the sides of the panel, and an upholstered cushion attached to the front surface of the upper portion of the panel.

10. A chair structure comprising: spaced standards; a chair seat mounted between said standards; a back panel attached at its opposite sides to the standards and having integrally formed rearwardly bowed upper and lower portions, said upper portion being inclined upwardly-rearwardly and said lower portion depending substantially vertically from the upper portion rearwardly of the seat; and a chair back mounted adjacent the front surface of said upper portion of the back panel.

20. A chair structure comprising: spaced standards; a chair seat mounted between said standards; a sheet metal back panel attached at its opposite sides to the standards and having integrally formed rearwardly bowed upper and lower portions, said upper portion being inclined upwardly-rearwardly and said lower portion depending substantially vertically from the upper portion rearwardly of the seat, and the metal of the panel joining the upper and lower portions thereof being drawn into a substantially horizontal ridge of substantial dimensions in the middle of the panel and fading out at the sides of the panel; and a chair back mounted adjacent the front surface of said upper portion of the back panel.

30. A chair structure comprising: spaced standards; a chair seat mounted between said standards; an integrally formed sheet metal back panel rearwardly bowed and provided with forwardly extending side wings for attachment of the panel to the standards and said panel having upper and lower portions, said upper portion being inclined upwardly-rearwardly and said lower portion depending substantially vertically from the upper portion rearwardly of the seat, and the metal of the panel joining the upper and lower portions thereof being rearwardly drawn into a substantially horizontal ridge of substantial dimensions in the middle of the panel and fading out at the sides of the panel; and a chair back mounted adjacent the front surface of said upper portion of the back panel.

40. A chair structure comprising: spaced standards; a chair seat mounted between said standards; an integrally formed sheet metal back panel rearwardly bowed and provided with forwardly extending side wings; forwardly extending wing clips secured to said side wings; fastening means for securing the wing clips to the standards respectively; said back panel having upper and lower portions, said upper portion being inclined upwardly-rearwardly and said lower portion depending substantially vertically from the upper portion rearwardly of the seat, and the metal of the panel joining the upper and lower portions thereof being rearwardly drawn into a substan-

tially horizontal ridge of substantial dimensions in the middle of the panel and fading out at the sides of the panel; and a chair back mounted adjacent the front surface of said upper portion of the back panel.

8. A chair structure comprising: spaced standards; a chair seat mounted between said standards; an upholstered chair back; wing clips secured to the rearward surface of the chair back at opposite sides thereof and having forwardly extending portions; fastening means for securing the wing clips to the standards respectively; a back panel having a socket at its upper edge embracing the upper edge of the chair back, said back panel having an upper portion lying adjacent the rear surface of the chair back and a lower portion depending from the upper portion rearwardly of the seat.

9. A chair structure comprising: spaced standards; a chair seat mounted between said standards; an upholstered chair back; wing clips secured to the rearward surface of the chair back at opposite sides thereof and having forwardly extending portions; fastening means for securing

15

the wing clips to the standards respectively with the chair back in an upwardly-rearwardly inclined position; a back panel having a socket at its upper edge embracing the upper edge of the chair back, said back panel having an upwardly-rearwardly inclined upper portion lying adjacent the rear surface of the chair back and a lower portion depending substantially vertically from the upper portion rearwardly of the seat.

10. A back panel for a chair structure comprising a one-piece sheet metal panel formed in two curved sections intersecting each other and an embossed ridge of graduated cross-section at the intersection.
